TOOL

Edmund A. Randall and Vernon B. Slifer,
New York, N. Y.

Application July 13, 1945, Serial No. 604,951

1 Claim. (Cl. 78—47)

(Granted under the act of March 3, 1883, as
amended April 30, 1928; 370 O. G. 757)

1

This invention relates in general to a new tool and in particular to a caulking tool.

In many construction operations it is found necessary to perform a caulking operation on two sides of a strip of material. The common practice in such a case is to caulk one side of the strip and then in a separate operation to caulk the other side. This naturally results in a waste of time and also sometimes results in an imperfect caulking job.

It is an object of this invention to provide a new caulking tool to caulk simultaneously a plurality of strips in one operation.

Further objects and advantages of this invention, as well as its construction, arrangement and operation, will be apparent from the following description and claim in connection with the accompanying drawings, in which:

Fig. 1 is a front elevation of the new caulking tool in an operating position.

Fig. 2 is a side elevation of the head of the tool shown in Fig. 1, taken along line 2—2.

A dual caulking tool 11 is positioned for a caulking operation upon a workpiece generally designated 12 that comprises a flat plate 13 having relatively narrow strips 14 mounted thereon.

The tool 11 comprises a shaft or handle 15 tapered at one end to a head 16. Projecting from the head 16 and preferably an integral part of the head are a pair of caulking lips 17 that are preferably rounded at the corners.

The lower surface of each of these lips 17 is characterized by being tapered partially to an edge and by having a flattened tip 18 at the lower extremity. Between the lips 17 there is a rectangular groove 19 which is adapted to receive comparatively snugly the strip 14 that is to be caulked to plate 13.

In the use and operation, the new caulking tool is placed on the workpiece 12 as shown in Figure 1 with strip 14 projecting into groove 19 and with lips 17 of the tool straddling the strip 14 and bearing against the surface of the plate 13. A conventional caulking operation is carried out except that the caulking operation is performed simultaneously on each side of the strip 14 and a perfect caulking job is simultaneously obtained on each side of the strip. The pressure of the caulking tool on each side of the strip 14 provides a supporting force to coact with the caulking force on the opposite side of this strip. Because of this supporting force it is thereby possible to obtain a good caulking job on a comparatively loosely mounted strip whereas in the

use of a conventional single caulking tool there is a tendency for the strip to be pushed to one side during the caulking operation.

By the use of this tool it is also possible to mount a strip loosely upon the surface of a crosspiece and to guide the strip into its correct position with the same tool that performs the actual caulking operation, thus eliminating the necessity for a frequently complicating system of wedges, braces, and other supports.

It is to be understood that various modifications and changes may be made in this invention without departing from the spirit and scope thereof as set forth in the appended claim.

15 The invention described herein may be manufactured and used by or for the Government of the United States of America for governmental purposes without the payment of any royalties thereon or therefor.

20 What is claimed is:
A caulking hand tool formed of a single piece only of bar-shaped material, said tool throughout the major portion of its length being of uniform cross section and forming a handle, said tool at one end being axially slotted to form a pair of spaced lips, said lips having substantially parallel opposed internal surfaces and tapered external surfaces forming each lip into a wedge shape, said lips being flattened along their edges, said edges being of convex semicircular shape of a diameter substantially equal to the diameter of the handle.
